UNITED STATES PATENT OFFICE.

JOHN A. CAMPBELL, OF SEATTLE, WASHINGTON, ASSIGNOR TO HUGH R. ROBERTSON, OF PORTLAND, OREGON.

LOG RAFT.

No. 800,263.

Specification of Letters Patent.

Patented Sept. 26, 1905.

Application filed January 31, 1905. Serial No. 243,560.

To all whom it may concern:

Be it known that I, JOHN A. CAMPBELL, a citizen of the United States, residing at the city of Seattle, county of King, State of Washington, have invented certain new and useful Improvements in Log Rafts; and I do hereby declare the following to be a full, clear, and exact description of the same.

My invention relates to the class of log rafts intended to be towed from the place where built to a destination where they are to be broken up and the logs used.

My invention consists in a raft comprising a lower or carrying component of relatively great beam and small draft, an upper or carried component resting upon top of the lower component, and suitable means for securing the two components together.

It also consists in the novel means for securing the two components together and the novel self-tightening tow-chain connections, all of which, together with the objects of my invention, I shall hereinafter fully describe.

Referring to the accompanying drawings, Figure 1 is a side elevation of my raft. Fig. 2 is a top plan, partly broken, showing the arrangement and connections of the fore and aft tightening-chains and the tow-chain. Fig. 3 is a central cross-section of the raft when first completed and before the settling together of the logs and the corresponding self-tightening of the chains. Fig. 4 is a similar section showing the relative position of the two components of the raft after the logs have settled together.

The raft comprises a lower or carrying component A and an upper or carried component B. The lower component consists of an assemblage of logs fashioned longitudinally in a "cigar" shape, as seen in Figs. 1 and 2, and in transverse section in an ellipsoidal shape, the ends and bottom being curved and the top flattened, as seen in Fig. 3, the major axis of the section being transverse, so that a maximum or relatively great beam is had with a minimum or relatively small draft. Chains C encircle the lower component A at suitable intervals and bind the logs together. The upper component B is also composed of logs and is fashioned longitudinally to a cigar shape, as seen in Fig. 1, while in cross-section it is approximately circular, as in Figs. 3 and 4. The

upper component B is borne upon the flattened top of the lower component A, the two being bound together by suitable means.

Before describing the connection of the two raft components I shall for the sake of clearness point out the object of this relative arrangement. This object is twofold—first, to enable me to make a very large raft, and, second, to provide for the self-tightening of the binding-chains during the voyage as the logs settle in closer to each other. The first of these objects is attained, or, rather, made possible, by providing a great breadth of beam for the lower or carrying component without correspondingly increasing its depth. In single symmetrical rafts as heretofore made an increase in beam means a corresponding increase in draft. The draft being limited to the depth of the harbors at the beginning and end of the raft's voyage, a limit is thus set for the size of the raft, and therefore of its contents. To increase the beam of a single raft without increasing its depth is destructive of stability; but by placing the upper or what may be termed the "deck-load" component, such as B, (here shown,) upon the top of the carrying component A the latter may be made very wide, and still remain of light enough draft to enter the harbors. Thus the aggregate number of logs in the two components which go to make the single structure may be enormously increased without affecting its draft and without detracting from its stability. In fact, the relative arrangement of the two components of the structure is such that the stability is even increased, for as the weight of the deck-load component causes it to sink from the initial position of Fig. 3 into the top of the carrying component the sides of the latter bulge up or rise, and the whole structure floats in the water in about the position shown in Fig. 4, the uplifted sides of component A protruding above the water, while the very bottom of component B sinks below the line. In this position the structure is stable and of light draft. The second object—namely, the tightening of the chains—is the direct result of the weight of component B upon them. During the voyage no matter how tightly the building-chains are initially shackled the logs settle closer together and the chains loosen; but with the upper component bearing down upon

the chains and sinking down into the lower component said chains are kept taut no matter how much the logs settle together. The arrangement of the chains and the connections of the two components are such as to produce this self-tightening result. Longitudinally-extending logs D D on the top of component A serve as a kind of cradle between which the upper component securely rests. Around the upper component at suitable intervals are chains, each of which is composed of two parts. One part E is shackled at e to the adjacent chain C of the lower component and thence passes in one direction between the two components and up around one side of the upper component to the top. The other part E' is shackled at e' to the same chain C of the lower component and thence passes in a direction opposite to the part E between the two components and up the opposite side of the upper component. The adjacent ends of the parts E and E' are shackled together on top of the upper component at e'. Thus it will be seen that the chains E E' are practically doubled where they cross, and they hold the upper component in such a way that any tendency to roll results in a tightening strain not only upon themselves, but upon the chains C as well, thereby tightening all the chains under all circumstances in the seaway. Short chains F extend between chains C and E E', just outside the cradle-logs D D and hold the latter in place.

In practice in order to relieve the chains of the rubbing weight of the raft components and to give them freedom enough to tighten I slip in pieces of wood G between the two components under the cradle-logs D D along-side of the chains C and other pieces of wood H between the cradle-logs D D and the upper component alongside of the chains E E'.

The arrangement of chains to tighten the raft longitudinally to pull the ends together and to tow the structure is shown in Figs. 1, 2 and is as follows: Secured to the rear end of the lower component A and thence extending forwardly along its top is a chain I, which in its course is secured to each of the chains C. This chain I terminates with a block i. A second chain J is secured to the forward end of component A and thence extends rearwardly along its top, being secured to each of the chains C, which it passes, and terminates with a block j near the block i. The tow-chain K enters the forward end of the upper component B and is inclined downwardly to and around block i, thence forwardly to and around block j, and thence back again to block i, to which it is secured. This forms a tackle by which in towing the ends of the chains I and J are pulled together, thereby tightening the raft longitudinally and also tightening all the encircling chains C and E E'.

Having thus described my invention, what 65 I claim as new, and desire to secure by Letters Patent, is—

1. A log raft comprising a lower, carrying component with encircling chains to bind its constituents together, an upper, carried component resting on top of the lower component and having independent chains to bind its constituents together, and means for securing the two components together. 70

2. A log raft comprising a lower, carrying component, chains encircling said component, an upper, carried component on top of the lower component, and resting upon the top of its encircling chains and means for holding the components together. 80

3. A log raft comprising a lower, carrying component, chains encircling said component, an upper carried component on top of the lower component, and resting upon its encircling chains and means for holding the components together, consisting of chains encircling the upper component, crossing below the same and secured to the chains of the lower component. 85

4. A log raft comprising a lower, carrying component with relatively large beam and small draft, an upper, carried component resting upon the top of the lower component and having a beam less than that of said lower component, and suitable means for fastening 95 the two components together.

5. A log raft comprising a lower, carrying component with relatively large beam and small draft, chains encircling said lower component at intervals, an upper, carried component resting upon top of the lower component and upon its encircling chains, said upper component having a beam less than that of the lower component, and suitable means for holding the upper component in place. 100 105

6. A log raft comprising a lower, carrying component with relatively large beam and small draft, an upper carried component resting upon the top of the lower component and having a beam less than that of said lower component, chains encircling the lower component at intervals, and other chains secured to said first-named chains and encircling the upper component at intervals. 110

7. In log raft comprising a lower, carrying component with relatively large beam and small draft, an upper, carried component resting upon the top of the lower component and having a beam less than that of said lower component, chains encircling the lower component at intervals, and other chains encircling the upper component at intervals, said last-named chains having their ends passing between the two components, crossing each other from opposite directions and secured to the chains which encircle the lower component. 115 120 125

8. A log raft composed of a lower, carrying component, an upper, carried component, rest-

ing upon the top of the lower component, longitudinally-disposed cradle-logs, on the lower component between which the upper component rests, and suitable means for securing the components together.

5. A log raft composed of a lower, carrying component, an upper, carried component, resting upon the top of the lower component, longitudinally-disposed cradle-logs on the lower component between which the upper component rests, and suitable means for securing the components together, consisting of chains encircling the lower component, and other chains encircling the upper component, said last-named chains having their ends passing between the two components, crossing each other from opposite directions and secured to the chains which encircle the lower component.

10. A log raft composed of a lower, carrying component, an upper, carried component, resting upon the top of the lower component, longitudinally-disposed cradle-logs on the lower component between which the upper component rests, and suitable means for securing the components together, consisting of chains encircling the lower component, and other chains encircling the upper component, said last-named chains having their ends passing between the two components, crossing each other from opposite directions and secured to the chains which encircle the lower component, and pieces inserted between the bearing-surfaces of said components and cradle-logs, said pieces being located beside 35 the chains to relieve them of the weight-pressure.

11. A log raft comprising a lower, carrying component, an upper, carried component rest-

ing on top of the lower component, means for securing the two components together, a chain 40 secured to the rear end of the lower component, extending forwardly and terminating with a block, a chain secured to the forward end of said lower component, extending backwardly and terminating with a block, and a 45 tow-chain extending from the forward end of the upper component and having its rear end passing as a tackle between the terminal blocks of the chains of the lower component to draw them together in towing the raft.

12. A log raft comprising a lower, carrying component, an upper, carried component resting on top of the lower component, chains encircling the lower component, chains encircling the upper component, crossing between 55 the components and secured at opposite sides to the encircling chains of the lower component, a chain secured to the rear end of the lower component extending forwardly and secured to the encircling chains of said lower 60 component and terminating with a block, a chain secured to the forward end of said lower component, extending backwardly and secured to the encircling chains of the lower component and terminating with a block, and a tow-chain 65 extending from the forward end of the upper component and having its rear end passing as a tackle between the terminal blocks of the chains of the lower component to draw them together in towing the raft.

In witness whereof I have hereunto set my hand.

JOHN A. CAMPBELL.
